DOBBY FINGER FOR LOOMS

Elbridge R. Holmes, Worcester, Mass., assignor to
Crompton & Knowles Loom Works, Worcester,
Mass., a corporation of Massachusetts

Application December 21, 1936, Serial No. 116,974

1 Claim. (Cl. 139—66)

This invention relates to dobbies used for selecting and shifting loom harnesses, and relates more particularly to the dobbies forming a usual part of such mechanisms. Two such dobbies are commonly provided for each loom harness, and these dobbies are mounted in closely parallel relation and with relatively slight clearance between adjacent fingers.

Difficulty is at times encountered by reason of the accumulation of lint and dirt between adjacent dobbies, which accumulations may cause two adjacent fingers to be raised, due to friction between the fingers, when the raising of one finger only is indicated by the pattern chain. Such inadvertent lifting of a second dobbie finger is objectionable and will usually cause a defect in the weaving.

It is the general object of my invention to provide an improved construction of dobbie finger by which such accumulations of lint and dirt will be reduced and largely eliminated.

It is desirable and customary to provide dobbies with a thickened lower peg-engaging edge portion, and it is a further object of my invention to provide an improved method of producing such a thickened edge portion.

My invention further relates to arrangements and combinations of parts which will be herein-after described and more particularly pointed out in the appended claim.

Two forms of the invention are shown in the drawing in which

Fig. 1 is a sectional side elevation of parts of a dobbie embodying my improvements;

Fig. 2 is an enlarged side elevation of one of my improved dobbies;

Fig. 3 is a plan view thereof, looking in the direction of the arrow 3 in Fig. 2;

Fig. 4 is a sectional elevation, taken along the line 4—4 in Fig. 2;

Figs. 5 and 6 are sectional elevations, illustrating my improved method of forming the dobbie finger shown in Figs. 2, 3 and 4;

Fig. 7 is a partial side elevation of a modified form of dobbie finger; and

Fig. 8 is a sectional elevation, taken along the line 8—8 in Fig. 7.

Referring to Fig. 1, I have shown a portion of a usual harness jack 10 pivotally connected to a dobbie back lever 11, to which upper and lower hooks 12 and 13 are pivoted at 14 and 15.

Dobby fingers 20 are mounted in closely parallel relation on a cross bar 21 and their outer ends are supported on a second cross bar 22 having spacing pins 23 for the ends of the dobbies.

fingers. Projecting end portions 24 of the fingers 20 underlie the lower hooks 13 or the lifter rods 25 for the upper hooks 12.

A pattern chain 26 is mounted on a pattern cylinder or roll 27 and the chain 26 is provided with chain bars 28 having pegs 30 adapted to engage the lower edges of corresponding fingers 20 when in uppermost position, and adapted to lift the fingers which are thus engaged.

All of the parts thus far described, with the exception of the fingers 20, are of the usual commercial construction and form no part of my invention.

Each finger 20, however, is of special construction and is provided with a large central recess 15 or opening 32 and with a thickened lower edge portion 33 of substantial height.

The preferred method of forming the fingers 20 is indicated in Figs. 5 and 6. The openings 32 are punched out at the same time that the fingers 20 are punched from sheet steel plates or by a subsequent punching operation. Each finger 20 is then inverted, so that the portion 35 above the opening 32 will be at the bottom, as indicated in Fig. 5. The finger is then placed over a rigid support or anvil 40, while a die or hammer 42 is firmly pressed downward against the portion of the finger supported above the anvil. This part of the finger is thus transformed to the thickened portion 33, as indicated in Fig. 30 6, and is preferably provided with the usual concave lower edge portion 37 for centering the pegs 30.

The thickened edge portion 33 is preferably about equal in length to the opening 32 and the relatively thin portion 35 is preferably about equal in height to the opening 32.

I thus not only provide an improved and effective method of thickening and shaping the lower edge portion 33 of the dobbie finger 20, but the large central opening 32 in itself also possesses the very desirable function of largely preventing such accumulation of lint and dirt as has previously caused defective operation.

It will be noted by reference to Fig. 1 that when the fingers 20 are in normal position, the openings 32 will be aligned so that a continuous passage of substantial cross section is provided from one end to the other of the series of dobbies. Lint and dirt entering between the portions 35 readily falls into the transverse passage formed by the openings 32, from which passage it will commonly clear itself or from which it may be quickly and easily removed manually.

Accumulation of lint and dirt between the closely adjacent thickened portions 33 is thus substantially eliminated, and the very objectionable lifting of non-indicated fingers by friction is avoided.

The thickened portions 33 are preferably of such height that the part 33 of a raised finger will not clear the part 33 of a lowered adjacent finger, thereby avoiding locking of the fingers in raised position.

In Figs. 7 and 8 I have shown a dobby finger 50 having openings 51 as previously described, but having the thickened lower edge portion 52 formed by twisting the part of the finger 50 below the opening 51 ninety degrees, instead of upsetting the edge portion as in the form previously described. This form of my invention is preferably produced by a combined twisting and press operation so that a concave lower surface 54 may be provided for the pattern pegs. In this construction, the thickening of the lower edge portion is substantially increased over the form shown in Fig. 4, and at the same time the

vertical dimension of the opening 51 is also increased.

With either form of my invention I attain the very desirable result of so reducing the possible friction between adjacent fingers that non-indicated finger lifting is substantially avoided.

Having thus described my invention and the advantages thereof, I do not wish to be limited to the details herein disclosed, otherwise than as set forth in the claim, but what I claim is:—

In a loom, a dobby finger having a thickened lower edge portion and a relatively thinner and wider upper edge portion and having a relatively large central opening through said finger in said thinner upper edge portion, said central opening being substantially equal in length to said thickened lower edge portion and bounded on one side thereby and being substantially equal in height to one-half of said thinner upper edge portion, and said opening substantially reducing friction between adjacent dobby fingers.

ELBRIDGE R. HOLMES.
